PAPER CARRIAGE FOR ACCOUNTING MACHINES

Walter A. Anderson, Bridgeport, Conn., assignor to Underwood Elliott Fisher Company, New York, N. Y., a corporation of Delaware

Application June 29, 1938, Serial No. 216,467

1 Claim. (Cl. 197—128)

This invention relates to paper carriages for accounting machines, and more particularly to a means for detachably securing certain parts of the front feed paper mechanism to the carriage proper.

The primary object of the present invention is to provide a clamping means which will hold the front feed paper guides in operative position on the carriage and which may be readily removed to facilitate the handling of rear fed paper.

With this and incidental objects in view, the invention consists of certain novel features of construction and combinations of parts, the essential elements of which are set forth in the appended claim, and a preferred embodiment of which is hereinafter described with reference to the drawings which accompany and form part of the specification.

In the drawings:

20 Figure 1 is a right side elevation of an accounting machine carriage embodying the invention.

Figure 2 is a detailed perspective view of the improved clamping device.

25 Figure 3 is a detailed rear elevation thereof, and

Figure 4 is a view similar to Figure 1, but showing the front feed guides in adjusted position.

30 The device is illustrated in connection with the type of carriage disclosed in United States Patent No. 2,060,954, issued to Oscar J. Sundstrand on November 17, 1936, and my United States application Serial No. 192,675, filed February 26, 1938, and is an improvement over the clamping mechanism disclosed in the application.

Referring to Figure 1, the carriage is mounted for transverse movement along a bed 1 by suitable roll and groove construction indicated generally at 2. A platen 3 is journaled at its ends in oppositely disposed side walls, such as 4, and is arranged to be rotated either manually or automatically.

45 The rear fed paper 5 is inserted downwardly over a paper table 7 extending across the carriage. The paper then passes downwardly around the platen between rear feed rolls such as 11, and bands such as 12, then rearwardly under a plate 14, and upwardly out of the carriage.

50 For introducing front fed sheets, upper and lower guides 15 and 16, respectively, are provided. The lower guides are formed as chutes and serve to guide the paper as it is inserted downwardly therein, and the upper guide is provided with an

edge guide 17 which assists in directing the paper laterally. The upper guides are pivoted on rods such as 18, that extend through the lower guides 16 and are secured to arms such as 19. Arms 19 are in turn secured to arms such as 20, pivoted on semi-cylindrical studs 21. Arms 20 are held in engagement with studs 21 by studs 22 secured in the carriage side walls. In operation, after the front fed paper is inserted, guides 16 are swung to the right about pivot studs 21, this movement also swinging guides 15 to the right. Figure 4 shows the parts in this position.

The upper ends of guides 15 are supported on a rod 23 extending between forwardly extending arms such as 24, fixed on the carriage side walls. 15

From a comparison of Figures 1 and 4, it is apparent that a flexible connection must be provided between guides 15 and rod 23 to allow guides 15 to move slightly upwardly and downwardly as the front feed guides 15 and 16 are moved from one position to another. It is also desirable to swing guides 15 from the position shown in full lines in Figure 1 to the position shown in dot and dash lines in this figure. This greatly facilitates handling of the rear fed paper. 25 To permit the above described movements of guides 15 and to hold the guides in proper position, the following clamping means is provided.

U-shaped brackets such as 25 are secured to the rear of guides 15. Oppositely disposed and identical clamp members 26 and 27, telescoping one within the other, are pivoted upon a pin 28 which passes through apertures in the bracket 25 and also through apertures 29 (Figure 2) in ears provided on clamp members 26 and 27. 35

The right ends of the clamp members are beveled inwardly and are provided adjacent the beveled portions with oppositely disposed V-shaped notches 30 of a size to fit neatly around rod 23. A spring 31 (Figure 2), connected between the clamp members, tensions the members toward one another. An upwardly extending projection 32 formed on member 27 and a depending projection 33 similarly formed on member 26 are arranged to bear against the bases of 45 the opposite members to limit the action of spring 31 and thereby hold the parts in convenient position to receive rod 23.

When the operator desires to remove guides 15 from the position shown in full lines in Figure 1 50 to the position shown in dot and dash lines therein, it is merely necessary to grasp the guide and give a slight pull toward the left. This spreads the clamp members 26 and 27 against the tension of springs 31, disconnecting guides 55

- 15 from rod 23. After the rear fed paper is handled, guides 15 are swung back to the right, toward the full line position shown in Figure 1, the beveled rear edges of the clamp members 26 and 27 guiding the assembly toward rod 23. The operator then exerts a slight pressure toward the right, causing the beveled ends of the members to spread the clamp members apart against the tension of spring 31, admitting rod 23 to notches 30. The tension of springs 31 then holds the clamping members and guides 15 against accidental displacement from this position.
- 10 Referring now to Figure 3, sleeves such as 34, adjustable along rod 23 by means of thumb screws such as 35, are provided to prevent lateral movement of the clamp members and guides 15. These sleeves are of just sufficient width to fit between the side flanges of clamping members 26 and 27.
- 15 20 While the form of mechanism herein shown and described is admirably adapted to fulfill the

objects primarily stated, it is to be understood that it is not intended to confine the invention to the one form of embodiment herein disclosed, for it is susceptible of embodiment in various forms, all coming within the scope of the claim which follows.

What is claimed is:

In a paper carriage having a platen, a front feed mechanism including a bail mounted for pivotal movement toward and away from the platen, a paper guide pivoted on the upper portion of the bail, a rod mounted on the frame of the carriage, and a clamping means mounted for a limited pivotal movement on the upper portion of the paper guide and provided with oppositely disposed jaws presenting beveled surfaces to the rod, so that the clamp will engage the rod when the paper guide is moved into paper receiving position.

WALTER A. ANDERSON. 20
